UNITED STATES PATENT OFFICE.

DONALD K. BAXTER, OF DAYTON, OHIO.

RAZOR DRIER.

Application filed August 2, 1922. Serial No. 579,268.

To all whom it may concern:

Be it known that I, DONALD K. BAXTER, a citizen of the United States of America, residing at Dayton, county of Montgomery, 5 State of Ohio, have invented certain new and useful Improvements in Razor Driers, of which the following is a full, clear, and exact description.

The present invention relates to driers 10 and particularly that type of driers in which artificial heat is employed as the active agent.

An object of the invention is to provide a compact drier adapted to receive a completely assembled safety razor or similar device to be dried therein.

Another object is to provide a drier having means for automatically discontinuing the artificial heat after it has operated the 20 desired length of time.

A still further object is to construct a drier adapted to be attached to the wall in any convenient location and provided with convenient and readily accessible means for 25 holding the razor while it is being dried and in which the razor may be allowed to remain after drying, ready for use when desired.

Further objects will be apparent from the 30 following description of the invention and from the drawings, in which

Fig. 1 is a perspective view of the drier showing a safety razor supported therein;

Fig. 2 is a vertical section on the line 2—2 35 of Fig. 1, part thereof being shown in elevation;

Fig. 3 is a bottom view of the cover portion of the drier showing the arrangement of the circuit control means therein;

Fig. 4 is a section on the line 4—4 of 40 Fig. 3;

Fig. 5 is a bottom view of the supporting body showing somewhat diagrammatically the arrangement of the heating element 45 thereon;

Fig. 6 is a side elevation of a modified form of drier, parts thereof being shown in section on line 6—6 of Fig. 7; and

Fig. 7 is a vertical section on the line 7—7 50 of Fig. 6.

The present invention, in its broad aspect, comprises a housing 20 which may be entirely open at the bottom as shown in Fig. 1 or which may be only partially open at the 55 bottom as shown in Figs. 6 and 7 for the

reception of a razor or other instrument to be dried.

Referring particularly to Figs. 1 to 5, which show a preferred embodiment of the invention, 21 is a supporting body or block 60 of material carrying a razor holder or heating unit 22 on its under side, and 23 is a hollow cover or top portion carrying in its interior suitable thermostatic means for controlling the operation of the heating element which is associated with the razor holder, and which will be hereinafter described.

The razor holder comprises a clip or supporting member 24 having downwardly and inwardly turned sides which are spaced apart, as shown, to provide a slot or channel by which the head 25 of a safety razor may be inserted from either end of the holder and held therein in contact with the heated plate 26, as shown in Fig. 1. A heating element 27 is placed between the upper part of the clip 24 and the plate 26, and all three parts are rigidly clamped together and to the underside of the supporting body 21 by 70 means of a screw 28 at each end thereof, as best shown in Fig. 2. The heating element 27 may be constructed, as shown in Figs. 2 and 5, or turns of suitable resistance wire 29 wound on a sheet of mica or other suitable 75 support and electrically insulated from the metallic clip 24 and metallic plate 26 by sheets of mica, one on each side of the heating element as shown by heavy black lines 80 in Fig. 2. The ends of the resistance wire 29 85 pass through cut-away portions (not shown) of the clip 24 adjacent diagonally opposite corners of the heating element and are fastened by any desired means to the screw-threaded binding posts 30 and 31 90 which serve to establish electrical connection between the heating element and the control means in the hollow cover 23.

It will be observed that the heating element 27, being clamped between the clip 24 and 100 the plate 26 will transmit its heat to these metallic members, which in turn will heat the head of the safety razor. As shown in Figs. 1 and 2, the inwardly turned sides of the clip 24 are cut away midway of their 105 length to receive a spring clip 32 the purpose of which is to hold the head of the razor in close metallic contact with the heated plate 26 by pressing upwardly upon the lower surface of the head. The spring clip 110

32, consists of a strip of spring metal bent to conform to the shape of the clip 24, with its middle portion clamped between the clip 24 and the supporting body 21, as shown in Fig. 2, and its ends pressing yieldingly against the lower face of the razor head, as best shown in Fig. 1. The ends of the spring clip are, of course, so arranged as to not interfere with the easy insertion of the

10 razor head in the clip 24.

The cover or top portion 23 of the drier has its under part hollowed out to provide (with body 21) a control compartment 46 for the reception of the electric terminals 15 and the thermostatic control means. The thermostatic control means consists of a bi-metal strip 33 having lateral extensions at one end which are apertured to receive the binding post 30 and the headed screw 34 by 20 which it is rigidly secured to the cover. As shown in Figs. 2 and 3, the bi-metal strip is secured at one end while the other end overhangs the ledge 35 and is free to move vertically with variations in temperature.

25 The free end of the bi-metal strip 33 is bent upwardly into the path of the enlarged head 36 of push rod 37 which carries at its opposite end a push button 38. The push rod 37 is adapted to slide longitudinally being 30 guided at one end by the push button 38 sliding in an aperture in the cover and at the other end by the apertured contact plate 39 which will be hereinafter described. Spring 40 surrounding the push rod 37

35 tends normally to hold the push rod to the left with its head 36 against contact plate 39 and out of engagement with the bi-metal strip. When the push button is pushed in, that is, moved to the right in Fig. 2, the 40 head 36 passes over the bent end of the bi-metal strip 33 and is latched thereby in the position shown. Referring now to Fig. 3, it will be seen that the contact plate 39 is an L-shaped plate with the short arm bent 45 down and apertured to guide the push rod 37, and the long arm secured in a plane parallel to the bi-metal strip by fastening screws 41.

Electric current for the drier is led in by 50 a flexible cord, one wire 42 being secured to contact plate 39, and the other wire 43 being secured to contact plate 44 which latter is secured in position by a fastening means, including binding post 31 already referred to. 55 When the push button 38 is pressed in and the bi-metal strip 33 is latched under the head 36 of the push rod 37, as shown in Fig. 2, it will be observed that an electrical circuit is made from wire 42, through contact 60 plate 39, push rod 37, bi-metal strip 33, binding post 30, heating element 27, binding post 31 and contact plate 44 to the other wire 43 connected to the other side of the circuit.

The drier is operated by inserting the 65 razor in the holder 22 and then pressing the

push button 38 until it is latched by the bi-metal strip 33 as shown in Fig. 2. This will close the electrical circuit, above described, and send current through the heating element 27 thereby heating the holder 22 70 and drying the razor. The supporting body 21 is provided with apertures 45 to facilitate the transference of heat through the supporting body to the control compartment 46 containing the bi-metal strip 33 and other 75 circuit control devices. As the temperature rises in the control compartment with continued operation of the heating element, the free end of the bi-metal strip gradually moves downwardly until it releases the push 80 rod 37 which snaps to its extreme left hand position thereby breaking the heating circuit.

The apertures 45 may, of course, be varied 85 as regards both their size and their number to expedite or retard the transference of heat to the control compartment 46, thereby varying the duration of the heating operation as desired. While the supporting body 21 is herein shown as made of thick insulating material with apertures 45 to facilitate the transference of heat, it will be understood that the apertures are not essential but may be entirely omitted, and the rate of heat 90 transference regulated by varying the thickness of the supporting body 21 or by using material of another heat conductivity, or by employing all three methods for regulating the rate of heat transfer, as desired. It has been found preferable in practice to regulate 95 the apparatus so as to produce a low heat sufficient to evaporate all the water in comparatively long time, for example 4 to 7 minutes, rather than to expose the razor to a higher heat which would, of course, evaporate the water more quickly but which would at the same time possibly subject the 100 razor to undesirable temperatures should the circuit control means fail for any reason to open the heating circuit. To adjust the length of the heating operation after the apparatus has been assembled, the cover 23 is provided with an adjusting screw 47 which bears against the bi-metal strip, as 105 best shown in Figs. 2 and 4.

The assembled supporting body 21 and cover 23 are carried by a supporting frame 48 which encircles the supporting body 21 closely, and is cut-away at opposite ends as shown to admit the razor into the holder 22 from either end. The supporting frame 48 is provided with apertured extensions at opposite ends by which the apparatus may be attached to any convenient supporting 110 means such as a wall.

Figs. 6 and 7 show a modified form of the apparatus which is substantially the same as Figs. 1 to 5 in the general arrangement of the parts, but which varies in certain details of construction which will be 115

pointed out. The housing 20 is provided with a control compartment 40 and a heating compartment 49 similar in function and relative position to the corresponding parts in Figs. 1 to 5. The supporting body 21^a is provided with open heating elements 27^a which are adapted to dry the razor by direct radiation and by the convection currents induced in the heated air in compartment 49. 5 The razor is held by guides 50 spaced apart to provide a holder by which the razor may be inserted from the front, as illustrated. The supporting frame 48^a surrounds the supporting body 21^a and is extended upwardly at the rear to close the control compartment. Ventilating apertures 51 may be provided in the wall of the housing or not, as desired, for the purpose of regulating the rate of temperature rise in the control compartment and consequently the duration of the heating operation.

The present invention provides a convenient and economical means for drying razors which need not be taken apart and dried piece by piece as heretofore. With this drier it is only necessary to rinse the razor to remove all extraneous matter, (preferably unscrewing the handle slightly to facilitate the entry of the water), insert the razor in the holder, and press the push button to close the circuit to the heater. After a short time the automatic control means will open the circuit to the heater, leaving the razor completely dry. Preferably the razor is left in the holder, as shown in Fig. 1, where it will be out of the way and ready for immediate use when desired. Besides the advantages pointed out, it is found in practice that the blade of a razor dried in the manner above stated will outlast several times the blade of a razor that is cleaned by the ordinary method which involves taking the razor apart and drying the blade with a towel, that is, the heat dried blade may be used without resharpening much longer than the blade not dried in this manner.

While the form of mechanism herein shown and described constitutes a preferred embodiment of one form of the invention, 50 it is to be understood that other forms might be adopted and various changes and alterations made in the shape, size, and proportion of the elements therein without departing from the spirit and scope of the invention.

55 What is claimed is as follows:

1. A razor drier comprising, in combination, a housing having an opening on the underside thereof, a heating element in said housing, and means for supporting a bladed and handled article with its blade adjacent the heating element in said housing and its handle projecting through said opening.
2. A razor drier comprising, in combination, a housing having a portion thereof cut away to form an opening, a heating ele-

ment in said housing and means for supporting a bladed and handled article with its blade adjacent the heating element in said housing and its handle projecting through said opening.

3. A device of the character described, comprising in combination, a housing, a heating element therein, means for supporting an article to be heated within the housing whereby it may be heated by said heating element, and means within the housing for automatically discontinuing the action of the heater after a predetermined period of heating.

4. A device of the character described, comprising in combination, a housing, a heating element therein, means for supporting an article to be heated within the housing whereby it may be heated by said heating element, and temperature responsive means in the housing for automatically discontinuing the action of the heating element.

5. A device of the character described comprising, in combination, a housing having heating and control compartments, heating means therefor in said heating compartment, means for supporting an article to be heated within the heating compartment whereby it may be heated by said heating means, means operable from the exterior of said housing for initiating the heating operation, and means wholly within the control compartment for automatically discontinuing the heating operation.

6. A device of the character described comprising, in combination, a housing having a plurality of compartments, heating means in one of said compartments, means for supporting an article to be heated within the housing whereby it may be heated by said heating means, and temperature responsive means wholly in another of said compartments for automatically discontinuing the action of said heating means.

7. A device of the character described comprising, in combination, a housing having a plurality of compartments, heating means in one of said compartments, and temperature responsive means in another of said compartments for automatically discontinuing the action of said heating means, said housing having provisions for regulating the transference of heat between said compartments.

8. In a device of the character described, a housing having a portion thereof cut away to form an opening adapted to receive a handled body therein, a heating device in said housing comprising a plate and means on one side of the plate for heating it, and means for supporting a handled body within the housing and for yieldingly holding the body portion thereof to be heated against the other side of said plate.

9. A device of the character described

comprising, in combination, a heating device, a supporting wall adapted to carry the heating device on one side thereof, and control means on the other side of the supporting wall operable directly by the heat of the said heating device for controlling the operation of said heating device.

10. In a device of the character described, a heating element, means for supporting the heating element, said means encircling the heating element and having an opening for receiving an object to be heated, and means including a hooked portion adjacent said opening for holding said object in position 15 for heating.

11. In a device of the character described, a heating element, means for supporting the heating element, said means including side walls extending downwardly below the heating element and open at the bottom to receive an object to be heated, and means extending laterally from the side walls for supporting the object in heating position adjacent the heating element.

25. 12. In a device of the character described, a heating unit comprising a supporting member having a main wall, a side wall extending laterally from the main wall and a flange extending laterally from the side wall 30 to provide with the main and side walls a channel for the reception of an article to be heated, and means adjacent a wall of the supporting member for heating the article.

13. In a device of the character described, 35 a heating unit comprising a supporting member having a main wall, a side wall extending laterally from the main wall and a flange extending laterally from the side wall to provide with the main and side walls a channel for the reception of an article to be heated, means adjacent a wall of the supporting member for heating the article, and means for pressing the article towards the heating means.

40. 14. In a device of the character described, a heating unit comprising a supporting member having a main wall, a side wall extending laterally from the main wall and a flange extending laterally from the side 45 wall to provide with the main and side walls a channel for the reception of an article to

be heated, heating means against the main wall of the supporting member, and means for yieldingly urging the article towards said main wall.

15. In a device of the character described, a heating unit comprising a supporting member having a main wall, a side wall extending laterally from the main wall and a flange extending laterally from the side wall to provide with the main and side walls a channel for the reception of an article to be heated, a flat heating element within the channel, means for holding the heating element against the main wall of the body member, and means holding the article against said holding means. 65

16. In a device of the character described, a heating unit comprising a supporting member having a main wall, side walls extending laterally from the main wall, and spaced apart flanges extending inwardly from the side walls to provide a flat channel for the reception of an article to be heated, heating means within the channel, and means 70 for yieldingly pressing the article towards the heating means. 75

17. In a device of the character described, a heating unit comprising a supporting member having a main wall, side walls extending laterally from the main wall, and spaced apart flanges extending inwardly from the side walls to provide a flat channel for the reception of an article to be heated, heating means within the channel, and 80 spring means intermediate the ends of the channel for holding the article against the heating means. 85

18. In a device of the character described, a heating unit comprising a supporting member having a main wall, side walls extending laterally from the main wall, and spaced apart flanges extending inwardly from the side walls to provide a flat channel open at both ends for the reception of 90 an article to be heated, heating means within the channel, and means for yieldingly pressing the article towards the heating means. 95

In testimony whereof I hereto affix my 10 signature.

DONALD K. BAXTER.
